UNITED STATES PATENT OFFICE.

LEONIDAS DOTY WEST, OF DENVER, COLORADO.

FUEL-SAVER AND SMOKE-CONSUMER.

1,390,946.

Specification of Letters Patent. Patented Sept. 13, 1921.

Application filed August 4, 1919. Serial No. 315,188.

To all whom it may concern:

Be it known that I, LEONIDAS DOTY WEST, a citizen of the United States, residing at Denver, in the county of Denver and State 5 of Colorado, have invented certain new and useful Improvements in Fuel-Savers and Smoke-Consumers; and I do declare the following to be a full, clear, and exact description of the invention, such as will enable 10 others skilled in the art to which it appertains to make and use the same.

My invention relates to improvements in smoke consuming and fuel saving devices and more particularly to a device of this 15 character which accomplishes the required end by supplying hot air directly over the fire-bed of furnaces, stoves, etc., the present form of the invention being intended principally for furnaces.

20 The principal object of the invention is to provide a device of the character described which may be mounted on the furnace door, which will supply the hot air to the fire-bed at a point remote from said door, and nevertheless will permit opening of the door for 25 coaling whenever necessary, this end being attained by the provision of a projectable and retractable hot air supply neck which is slidable through an air heater fixedly carried on the door.

30 A further object of the invention is to provide an operating handle for the projectable and retractable neck, carrying means for controlling the amount of air entering the heater.

35 A still further object is to make provision for allowing a predetermined amount of air to enter the neck at all times, regardless of the amount entering the body of the heater.

40 An additional object is to provide the neck with restricted passages for admitting the hot air thereto from the air heater, whereby the travel of the air is retarded to insure maximum heating thereof.

45 With the foregoing objects in view, the invention resides in the novel construction and arrangement of parts hereinafter described and claimed, reference being made to the accompanying drawings.

50 Figure 1 is a central vertical longitudinal section showing my invention attached to a furnace door and illustrating the air supply neck projected for use.

55 Fig. 2 is a view similar to Fig. 1 but showing the neck retracted.

Fig. 3 is a horizontal section with parts in plan, as indicated by line 3—3 of Fig. 1.

Figs. 4, 5 and 6 are vertical transverse sections on the planes indicated by the lines 4—4, 5—5, and 6—6 respectively of Fig. 1. 60

Fig. 7 is a side elevation of the projectable and retractable neck.

Figs. 2^a and 2^b are detail sections on the plane of lines 2^a 2^a and 2^b 2^b of Fig. 2.

In carrying out my invention, I secure an air heater 1 to the coaling door 2 or any other suitable part of a furnace or stove, in such manner as to subject it to the heat from the fire-box; provide air inlet means for said heater; and slidably mount an air discharge 70 neck 3 in said heater for projection therefrom to supply the heated air to the fire-bed at a point rather remote from said heater, making suitable provision not only for projecting said neck, but for retracting it to 75 allow the door to be opened for coaling; and I prefer to provide means for controlling the amount of air entering the heater, and a constantly open passage 5 for continually supplying a quantity of air to said neck. 80 The air entering the casing 1 is heated by the latter and to insure maximum heating of such air before it is allowed to escape into the neck 3, I provide said neck with one or more restricted air passages 6, and the air 85 is thus retarded in its passage through the device, to such an extent as to cause heating to the required temperature.

The features briefly described above may be incorporated in numerous ways, but in the 90 preferred embodiment of my invention, the construction described below is followed.

The heater 1 comprises a cast metal casing which may well be in somewhat the shape of a pyramid as shown, with an opening 7 at its smaller end, and attaching flanges 8 at its other end, the latter end being open for communication with the usual damper openings 9 of the coaling door 2. A hood plate 10 is located on the exterior of the door 100 and extends over the openings 9, said hood plate and the heater 1 being secured in place by bolts 11 as shown. The plate 10 is provided with an air inlet opening 12 which is by preference elongated horizontally as illustrated in Fig. 5, and the air entering this opening, passes through the openings 9 into the heater 1 to be heated by the latter and discharged into the neck 3. 105

The neck 3 is of tubular form and slides 110 freely through the opening 7, being preferably somewhat flattened on opposite sides and provided with guide ribs 13. One end of the neck 3 is provided with any suitable

hot air discharge nozzle 14 which is preferably of the arcuate shape shown, and this nozzle is detachable to allow others to be substituted if desirable or necessary. The 5 other end of the neck 3 is closed at 15 with the exception of the passages 6, and one of said passages 6 communicates with a passage 5 which is formed in a contracted stem 16 which projects from the closed end 15 in 10 line with the axis of the neck. A handle rod 17 is connected with the outer end of the stem 16 and by sliding said rod inwardly, the neck 3 may be projected to position the nozzle 14 over the fire-bed, while an outward 15 pull on said rod will retract said neck in the heater 1 to allow opening of the door 2. I prefer to pivot the handle rod 17 to the stem 16 in order that it may swing downwardly when the door is to be opened, so as to interfere in no manner with opening of said 20 door sufficiently for coaling.

In most forms of the device, the handle rod 17 is equipped with the valve means 4 for controlling the entrance of air through 25 the opening 12, but in some instances, other air control means might be utilized. The means 4 comprises a damper plate 19 fixedly carried by the rod 17 and provided with plug means 20 adapted to enter the opening 30 12 in a non-rotatable manner, to prevent turning of the neck 3 after it is properly projected for use. When the handle is retracted however it may be turned to raise the depending nozzle 14, should this be necessary to open the door. Reinsertion of the 35 plugs 20 in the opening 12, when the neck is thus inverted, will hold it against accidental rotation. When the handle is forced inwardly and the neck thus projected, the 40 plate 19 substantially covers the opening 12 and only a small amount of air is allowed to enter the hood 10, between the latter and the plate in question, and through openings 21 formed in said plate.

45 The plate 19 may be secured to the rod 17 in any suitable manner and I have shown said plate provided with parallel lugs 22 straddling said rod, one of said lugs being provided with a set screw 23 contacting with 50 the rod. By this arrangement, the plate may be adjusted on the rod to control the amount which the neck 3 may be projected, but maximum projection of said neck is controlled by a rib 24 on the inner end of said 55 neck. When the parts are in operative position as seen for instance in Fig. 1, the plate 19 substantially covers the opening 12 and said plate then rests on a horizontal ledge 25 which extends outwardly from the hood 60 10. The lugs 20 are then received rather snugly in the opening 12 so that the neck 3 and parts movable therewith are held against rotation. When the rod 17 is pulled outwardly to an extent which withdraws the

65 lugs 20 from the opening 12, the plate 19 clears the ledge 25 and hence said rod may be rotated to invert the neck 3, which is usually advantageous when opening the door 2 for coaling. When the door is again closed, or prior to such closing, with the neck 70 3 and associated parts still in an inverted position, the lugs 20 may be forced part way into the opening 12 which will hold these parts against rotating to assume their normally operative positions, with the nozzle 75 14 declining rearwardly. It will be seen however that due to the eccentric positioning of the plate 19 on the rod 17, said plate will strike the ledge 25 and limit the inward movement of the rod and parts connected 80 therewith. Closing of the opening 12 is thus prevented so that an unusual amount of fresh air will enter the fire-box through the device to prevent excessive smoking after coaling.

85 In addition to the function above assigned to the rib 24, it serves to prevent the escape of an undesirable amount of air from the heater 1 around the neck 3, if the plate 19 is in such a position on the rod 17, as to allow 90 said rib to reach the opening 7. When the neck is pulled back sufficiently however, to move the rib 24 away from the opening 7, rapid discharge of air is allowed from the heater 1 through said opening 7, due to the 95 flattened sides of the neck.

The device may be operated in the most 100 advantageous manner, according to conditions, but immediately after coaling, it is desirable to allow maximum air to enter through the opening 12. This air impinges on the highly heated casing and the neck sliding therein and is thus expanded and heated to a high degree, escaping both through neck 3 and the opening 7. The 105 highly heated and expanded air which passes through the neck 3 is discharged through the nozzle 14 directly onto the fire-bed and mixed with the gas and smoke from the fresh coal, causing combustion of such 110 gases and consequently consuming the smoke. A suitable time after coaling, the neck may be fully projected and the opening 12 at the same time covered by the plate 19, but a small amount of air continues to 115 enter as above described. This air is heated as it passes through the device and insures perfect combustion in the fire-box.

120 Whenever the door 2 is to be opened, the handle rod 17 is pulled rearwardly and 125 swung downwardly around the pivot 18, so that the heater 1 and the nozzle 14 will clear the door frame and the handle will not strike the exterior of the furnace. The door may thus be opened to such an extent as to prevent the device from obstructing the coaling operation. If the heater 1 is attached in such manner as to allow the noz-

zle 14 to normally project below the dead plate of the door frame, said nozzle may be inverted to clear said plate, by turning the handle, but the shape of the plate 19 and 5 the ledge 25 will prevent the fireman from again completely projecting the nozzle while in an inverted position, as before explained.

The device is highly efficient and in every 10 way desirable, having been given practical and stringent tests; and particular emphasis is laid upon the discharge neck sliding through the heater; upon the restricted openings 6; upon the constantly open passage 15 5; and upon the valve means for not only controlling the amount of air entering the heater, but for permitting projection of the neck 3 to any required extent, according to conditions which may be encountered, such as the rearward depth of 20 the fire-box, and the width of the dead plate. In all cases where rib 24 is used, it of course controls the maximum amount which the neck may be projected inwardly. Since 25 probably the best results are obtainable from the details disclosed, they may well be followed, but within the scope of the device as claimed, the invention may be embodied in numerous forms other than that 30 shown, and need not in all cases be mounted on a door.

I claim:

1. In a fuel saver and smoke consumer, an air heater adapted to be mounted in a 35 stove or furnace in such manner as to be subjected to heat, said heater having air inlet means, an air discharge neck freely slideable through said heater and projectable therefrom, said neck having an air inlet 40 communicating with the interior of said heater and having a hot air outlet, and means connected with said neck and adapted to extend to the exterior of the stove or furnace for projecting and retracting said 45 neck.

2. A structure as specified in claim 1, the air inlet of said neck being restricted with respect to the inlet means of said heater to retard the discharge of air through said 50 neck and insure maximum heating thereof.

3. A structure as specified in claim 1, together with a passage for admitting a quantity of air to said neck from the atmosphere, without passage through said heater.

55 4. A structure as specified in claim 1, together with an extension on said neck adapted to extend to the exterior of the stove or furnace when the neck is retracted, and a passage formed through said extension and communicating with the interior of said neck for supplying a quantity of unheated atmospheric air thereto when the neck is retracted.

5. A structure as specified in claim 1, together with means controlled by said pro-

jecting and retracting means for controlling the amount of air entering the heater through said air inlet means thereof.

6. A structure as specified in claim 1, together with a damper plate on said projecting and retracting means for controlling the amount of air entering said heater through said air inlet means thereof.

7. A structure as specified in claim 1, said neck projecting and retracting means comprising an extension on said neck adapted to extend to the exterior of the stove or furnace through said air inlet means of the heater, and a handle rod connected with said extension for projecting and retracting 80 said neck, and means mounted on said handle rod for controlling the entrance of air through said air inlet means.

8. A structure as specified in claim 1, said neck projecting and retracting means comprising an extension on said neck adapted to extend to the exterior of the stove or furnace through said air inlet means of the heater, and a handle rod connected with said extension for projecting and retracting 90 said neck, and a damper plate secured on said handle rod for controlling the entrance of air through said air inlet means.

9. A structure as specified in claim 8, together with plug means on said damper plate for reception in said air inlet means of the heater.

10. A structure as specified in claim 7, said air controlling means being adjustable along said handle rod to limit the projection 100 of said neck.

11. A structure as specified in claim 8, said damper plate being adjustable along said handle rod to limit the projection of said neck, and a set screw for locking said 105 plate in adjusted position.

12. A structure as specified in claim 1, said neck having a depending outlet end; the means for projecting and retracting said neck serving also for rotating it when desired to elevate said discharge end, means on said projecting and retracting means for controlling the entrance of air to the heater, and means coacting with said air controlling means to prevent closing of the latter 110 while said neck is inverted from its normal position.

13. A structure as specified in claim 1, said neck having a depending outlet end; the projecting and retracting means for said 120 neck comprising an extension on said neck adapted to project to the exterior of the stove or furnace through an air inlet means of said heater and a handle rod connected with said extension and adapted for projecting and retracting said neck and for inverting it to elevate said outlet end; a damper plate mounted on said handle rod for controlling the entrance of air through said air inlet means and means coacting with said 125

plate to prevent closing of the latter when the neck is inverted from its normal position.

14. A structure as specified in claim 1, 5 said neck having a depending outlet end; the projecting and retracting means for said neck comprising an extension on said neck adapted to project to the exterior of the stove or furnace through the air inlet means 10 of said heater, and a handle rod connected with said extension and adapted for projecting and retracting said neck and for inverting it to elevate said outlet end, a damper plate mounted on said handle rod for controlling the entrance of air through said air 15 inlet opening, said rod being connected eccentrically with said plate, and a relatively fixed lug coacting with said plate to prevent closing of the latter while the neck 20 is inverted from its normal position.

15. The combination with a furnace door having a plurality of openings, of an air heating casing at the inner side of said door communicating at one end with said openings and having in its other end an opening, 25 a tubular neck slideable through said last named opening and having a restricted passage at one end establishing communication between its interior and said casing, the other end of said neck having a hot air outlet, an extension projecting from said first named end of said neck through one of said air inlet openings, a hood on the exterior of 30 said door extending over said air inlet openings and being itself provided with an air inlet opening through which said extension projects, and a handle connected with said extension for projecting and retracting said neck.

40 16. The combination with a furnace door having a plurality of openings, of an air heating casing at the inner side of said door communicating at one end with said openings and having in its other end an opening, 45 a tubular neck slideable through said last named opening and having a restricted passage at one end establishing communication between its interior and said casing, the other end of said neck having a hot air outlet, an extension projecting from said first named end of said neck through one of said air inlet openings, a hood on the exterior of 50 said door extending over said air inlet openings and being itself provided with an air inlet opening through which said extension projects, a handle connected with said extension for projecting and retracting said neck, and means on said handle for controlling the entrance of air through the opening 55 of said hood.

60 17. The combination with a furnace door having a plurality of openings, of an air heating casing at the inner side of said door communicating at one end with said openings and having in its other end an opening,

ing, a tubular neck slideable through said last named opening and having a restricted passage at one end establishing communication between its interior and said casing, the other end of said neck having a hot air outlet, an extension projecting from said first named end of said neck through one of said air inlet openings, a hood on the exterior of 70 said door extending over said air inlet openings and being itself provided with an air inlet opening through which said extension projects, a handle rod connected with the outer end of said extension for projecting and retracting said neck, and a damper plate on said handle rod for controlling the 75 entrance of air through the inlet opening of said hood.

18. The combination with a furnace door having a plurality of openings, of an air heating casing at the inner side of said door 80 communicating at one end with said openings and having in its other end an opening, a tubular neck slideable through said last named opening and having a restricted passage at one end establishing communication 85 between its interior and said casing, the other end of said neck depending and forming a hot air outlet, an extension projecting from said first named end of said neck through one of said air inlet openings, a hood on the exterior of 90 said door extending over said air inlet openings and being itself provided with an air inlet opening through which said extension projects, a handle connected with said extension for projecting, 95 and retracting said neck and for inverting the same to elevate its outlet end; and coacting means on said hood and handle to prevent maximum projection of said neck while 100 in an inverted position.

19. The combination with a furnace door having a plurality of openings, of an air heating casing at the inner side of said door communicating at one end with said openings and having in its other end an opening, 110 a tubular neck slideable through said last named opening and having a restricted passage at one end establishing communication between its interior and said casing, the other end of said neck depending and forming a hot air outlet, an extension projecting from said first named end of said neck through one of said air inlet openings, a hood on the exterior of 115 said door extending over said air inlet openings and being itself provided with an air inlet opening through which said extension projects, a handle connected with said extension for projecting, and retracting said neck and for inverting the same to elevate its outlet end, means on 120 said handle for controlling the entrance of air through the inlet opening of said hood, and means on said hood coacting with said air controlling means to prevent closing of the latter while said neck is inverted.

20. The combination with a furnace door having a plurality of openings, of an air heating casing at the inner side of said door communicating at one end with said openings and having in its other end an opening, a tubular neck slidable through said last named opening and having a restricted passage at one end establishing communication between its interior and said casing, the other end of said neck depending and forming a hot air outlet, an extension projecting from said first named end of said neck through one of said air inlet openings, a hood on the exterior of said door extending over said air inlet openings and being itself provided with an air inlet opening through which said extension projects, a handle rod connected with said extension for projecting, and retracting said neck for inverting the same to elevate its outlet end; a damper plate secured on said rod for controlling the entrance of air through the inlet opening of said hood, and a lug carried by said hood and coacting with said plate to prevent closing of the latter while said neck is inverted.
21. In a fuel saver and smoke consumer, an air heating casing adapted to be mounted in a stove or furnace in such manner as to be subjected to heat, said casing having air inlet means and an outlet opening, a tubular neck slidable freely through said opening, said neck having means for admitting air to its interior from said casing, and also having air discharge means, means operable from the exterior of the stove or furnace for projecting and retracting said neck, and valve means on said neck within said air heating casing adapted to normally seal the opening around the neck, said opening however permitting the direct escape of air from said casing when said neck is withdrawn sufficiently to space said valve means from the opening.

In testimony whereof I have hereunto set my hand.

LEONIDAS DOTY WEST.
